LAUNDRY APPLIANCES

Florence H. Figura, Robertson, Mo.

Application October 15, 1951, Serial No. 251,286

5 Claims. (Cl. 38—111)

This invention relates to improvements in laundry appliances, and more particularly to an improved laundry rack for supporting and protecting articles during the pressing thereof.

An important object is realized in providing a laundry holder and shielding member that is adapted to be positioned on the floor, in underlying relation with an ironing board, and an elongated rack operatively connected to the laundry holder by a collapsible rack-supporting structure which normally supports and retains the rack in the preferred horizontal position at substantially the same working level as the ironing board, but in spaced relation therewith. This structure greatly facilitates the ironing of sheets, spreads, table-cloths and like laundry by affording a convenient supporting means for them as they are being pressed. The articles are protected as against soiling prior to ironing, and thereafter are folded or draped over a supporting rack conveniently located at the rear of the pressing table. The pressing of large flat pieces particularly may be carried out expeditiously with the use of my improved rack.

An objective is attained by the inclusion of a swingable laundry protector panel pivotally connected to the laundry holding member which, in use, disposed on the floor beneath the ironing board in an extended but inclined position, thus to provide a convenient and efficient holder and protector for unpressed pieces, yet which does not utilize foot space below the table. The swingable panel cooperates with a floor panel to contain the unironed laundry, and serves in a measure to prevent it from coming in contact and interfering with the movements of the presser.

Still another object of the present invention is attained in an auxiliary rack assembly having structural and other useful features especially adapting the same for the reception of the larger articles which may be folded directly thereupon during the ironing process, and otherwise provide additional rack space for clothes hangers.

It is also an important object hereof to provide a combined laundry protector and rack device which is especially simple, practical, compact and durable in construction, easy to clean and inexpensive to manufacture, and particularly a device of this character that may be collapsed into folded arrangement for storage or shipping purposes, and readily expanded into a condition for use.

The foregoing and other objects of the invention will more clearly appear from the following detailed description of a preferred embodiment, particularly when considered in connection with the accompanying drawing, in which:

Fig. 1 is a perspective view of the combined laundry protector and rack assembly shown in operative position with an ironing board;

Fig. 2 is a rear elevational view of the protector and rack assembly shown in Fig. 1, and

Fig. 3 is a side view of the laundry protector and rack assembly in a folded, partly closed position.

Referring now by characters of reference to the drawing, it may be noted from Fig. 1 that the combined laun-

2

dry protector and rack assembly, generally designated at 10 and later fully described, will be expanded and normally located in the shown operative position with respect to any of the common types of ironing boards, one of 5 which is indicated at 11 and illustrated by broken lines.

A laundry holder and shielding floor panel 12 of the device 10 provides a floor frame 13 consisting of a right angle strip forming an integral, substantially U-shaped configuration with the inner surfaces of the angle strip 10 being faced inwardly, thus presenting a smooth, regular periphery. The floor frame 13 consists of spaced, opposite side portions and an end portion 19 that connects an end region of each side portion. Another laundry holder and protector panel 14 is pivotally attached to the U-shaped floor frame 13. Panel 14 includes a swingable frame 15 that is formed by a flat strip to provide a substantially rectangularly shaped structure, the swingable frame 15 consisting of spaced, opposite side portions and an end portion 20 that connects an end region of each of 15 the side portions of frame 15. The other end regions of the side portions of frame 15 are pivotally connected by pins 16 to the other end regions of the side portions of floor frame 13. The above description reveals a preferred construction of the framework of the respective 20 laundry protecting panels 12 and 14, yet should be understood in an informative sense, it not being intended to restrict.

The swingable protector panel 14, and hence swingable frame 15 is limited in its extended angular displacement 30 by a stop means which consists of inturned tabs 17, formed from the end of the side portions of floor frame 13 in such manner as to abut and engage the adjacent side portions of the swingable frame 15 upon displacement of frame 15 from a folded, nested position within the U-shaped frame 13 to the position shown in Fig. 1. It is apparent that the stop means interconnects the adjacent side portions of the frames 13 and 15 to limit the angular displacement of and to retain the swingable frame 13 in an extended, inclined position.

40 A flexible material 18, for example canvas or other washable cloth, is detachably secured to the frames 13 and 15, the canvas substantially covering and bridging the underside of the cooperating frames 13 and 15, to provide panel members 12 and 14. The end portions of the canvas 18 are looped respectively over the end portion 19 of the U-shaped floor frame 13 and over the end portion 20 of swingable frame 15, and detachably secured by a plurality of snap fasteners 21. This detachable connection permits the canvas to be disassembled 45 quickly and easily from about the panel frames, washed and as rapidly re-assembled for use. Of course, it is apparent that each laundry protecting panel may be constructed of a separate rigid or flexible sheet material, but the construction described provides a preferred assembly in the interests of realizing a compact, lightweight, 50 easy to clean laundry protector.

When the novel device 10 is expanded and in use, the larger laundry holding panel 12 is located on the floor, in underlying position with respect to the ironing board 11, and the swingable panel 14 is maintained in an upwardly inclined position (Fig. 1). The panels cooperate to provide a clean container, which holds the unironed laundry, and hence prevents it from being soiled by contact with the floor. In addition to other functions, the swingable panel 14 serves to guide and direct the unironed portion, of the article being ironed, upwardly to the overlying ironing board 11, and is disposed at an angle from the floor such that ample space is provided the person ironing for complete freedom of movement.

70 A collapsible rack assembly is secured to and supported by the horizontally disposed laundry holding panel 12, in the region opposite the pivotal connection of swingable

panel 14, the assembly including a bar 22 normally supported and retained in a horizontal plane, substantially at the level of the ironing board 11. The rack assembly further provides right angle extension arms 23 secured at one end to each extremity of bar 22, and extended downwardly, as viewed in Figs. 1 and 2, for pivotal connection with coacting right angle extension arms 24. The latter extension arms 24 normally lie with one end portion in overlapping relation with an arm 23, and with the opposite end pivotally attached by pins 25 to the inner face of the side portion adjacent end portion 19 of the U-shaped floor 13. The pivoted extension arms 23 and 24 are arranged so that the lower angle arms 24 open toward the swingable panel 14, and the upper angle arms 23 overlap the respective cooperating arm 24 and open outwardly toward the opposite end of the U-shaped frame 13. This arrangement attains greater strength and rigidity in the support of bar 22, and provides a stop means which limits the pivotal movement of and locks the extension arms 23 and 24 in the fully extended, aligned position shown in Figs. 1 and 2.

Braces 26 are pivotally fastened at one end thereof by pins 27 to the outer face of an upper extension arm 23, at a point above the pivot connection 28, and have the opposite end pivoted to the end of the side portion adjacent the end portion of the U-shaped floor frame 13. These braces 26 serve to reinforce the locking action of the coacting extension arms 23 and 24, the braces 26 and extension arms 23 and 24 constituting a rack-supporting means that serves to maintain and support the raised bar 22 in substantially the plane of the ironing board 11, but in horizontally spaced relation therewith. In the extended position, as the article is ironed, it may be folded over the bar 22 without permitting any portion to become soiled or wrinkled from contact with the floor, and hence be arranged immediately for storage or use after a single ironing.

Bar 22 is of a tubular structure, and is of sufficient internal diameter and length to receive and house an auxiliary bar 29, the latter bar providing a gripping portion 30 which projects from bar 22 and which may be utilized to extend the slideable auxiliary bar to any selective position on either side of bar 22. Without intending to restrict, it may be noted as a preference that the movable auxiliary bar 29 is constructed of solid wood, and is fitted with reasonably close tolerance in bar 22. When slidably moved to an extended position, the auxiliary bar 29 may serve the same function as and assist bar 22 in supporting the finished ironed material in a folded or draped arrangement as it leaves the ironing board 11, or the auxiliary bar may be used conveniently to support hangers.

Fig. 3 shows the combined laundry protector and rack assembly 10 in a collapsed, partly closed position. The swingable frame 15 has been angularly displaced to an overlapping and nesting relation with the cooperating horizontal floor frame 13. Also, the interlocking relation between the pivoted right angle extension arms 23 and 24 has been broken, thereby permitting the arms to be folded in nested arrangement within the U-shaped frame 13. Thus, it is obvious that the laundry protector and rack assembly is particularly adaptable by its novel construction, to be quickly and easily collapsed into a convenient compact form for storage or shipping.

The use of the laundry protector and rack device 10 is thought to have become apparent from the foregoing detailed description, but in the interests of further clarity and completeness, it will be noted that the assembly may be readily expanded for use by placing the larger laundry panel 12 horizontally on the floor, raising the bar 22 to the uppermost position as shown in Fig. 1, locking the extension arms 23 and 24 in rigid alignment, and raising the swingable panel 14 to the position determined by the stop tabs 17. The horizontal floor panel 12 is moved to a position underlying the ironing table such that bar 22 will be located substantially parallel to and in spaced

relation with the ironing board margin opposite the operator. When expanded and placed in this position, as in Fig. 1, the laundry protector and rack device is ready for use.

5 The operator then places the unironed laundry upon the canvas covered panels and proceeds to iron. As an article is ironed, the operator folds or drapes the finished portion over bar 22, reversing the material from one side of the rack to the other, without permitting any portion to contact the floor. If the article being ironed is very large, for example a sheet, curtain or bed-spread, it may be advisable and convenient to extend the auxiliary bar 29, which augments the effective length of rack structure. The use of the rack assembly in this manner permits the finished ironed article to be folded for storage or immediate use with only a single ironing operation.

10 The unironed portion of the material is contained by the canvas covered panels, thus protecting the article from being soiled. The front swingable panel 14 assists in containing the laundry, serves to direct and guide the unironed portion upwardly to the ironing board, and provides the maximum shielding area yet provides ample leg and foot space for the operator.

15 Although the invention has been described by making detailed reference to a single preferred embodiment, such detail is to be understood in an instructive, rather than in any restrictive sense, many variants being possible within the scope of the claims hereunto appended.

I claim as my invention:

20 1. In a laundry protector and rack assembly, the laundry protector comprising a floor frame having opposite side portions and an end portion, a swingable frame having opposite side portions and an end portion, one end region of each side portion of the swingable frame being pivotally attached to one end region of each side portion of the floor frame, a stop means carried by a side portion of one of said frames and engageable with an adjacent side portion of the other said frame, said stop means retaining the swingable frame in an extended, inclined position, a flexible material substantially bridging the frames, said material being detachably secured to the respective end portions of each frame, the rack assembly being of inverted U-shape, the legs of the U-shaped rack comprising a pair of pivotally connected extension arms, and the connecting member of said U-shaped rack comprising a bar, one of said arms of each leg being secured to the bar, the other arm of each leg being pivotally connected to a side portion of the floor frame adjacent the end portion, a stop means interconnecting said extension arms which limits the pivotal movement of and locks the extension arms in extended position, and a brace connected to one of said extension arms at a distance spaced from the pivotal connection of said arms, and connected to a portion of said floor frame.

25 2. In a laundry protector and rack assembly, the laundry protector comprising a floor frame having opposite side portions and an end portion, a swingable frame having opposite side portions and an end portion, one end region of each side portion of the swingable frame being pivotally attached to one end region of each side portion of the floor frame, a stop means carried by a side portion of the floor frame, said stop means being adapted to abut the adjacent side portion of the swingable frame, whereby to retain the swingable frame in an extended position, a flexible material substantially bridging the frames, said material being detachably secured to the respective end portions of each frame, the rack assembly being of inverted U-shape, the legs of the U-shaped rack comprising a pair of pivotally connected extension arms, and the connecting member of said U-shaped rack comprising a bar, one of the arms of each leg being secured to the bar, the other arm of each leg being pivotally connected to a side portion of the floor frame adjacent the end portion, a stop means interconnecting adjacent portions of said extension arms which limits pivotal movement of and locks

said arms in extended position, and a brace pivotally connected to one of said extension arms and pivotally connected to the side portion of the floor frame adjacent the end portion.

3. In a laundry protector and rack assembly, the laundry protector comprising a floor frame having side portions and an end portion, a swingable frame having side portions and an end portion, one end region of each side portion of the swingable frame being pivotally connected to one end region of each side portion of the floor frame, a stop means interconnecting adjacent side portions of the frames which limits the angular displacement of the swingable frame, a flexible material substantially bridging the frames, said material being detachably connected to the respective end portions of each frame, the rack assembly being of inverted U-shape, the legs of the U-shaped rack comprising a pair of pivotally connected extension arms, and the connecting member of said U-shaped rack comprising a bar, one of said arms of each leg being connected to said bar, the other said arm of each leg being pivotally connected to a portion of the floor frame, stop means interconnecting adjacent portions of said arms to retain said arms in extended position, and a brace pivotally connected to an arm connected to the bar and pivotally connected to a portion of the floor frame.

4. In a laundry protector and rack assembly, the laundry protector comprising a floor frame normally located in a horizontal position on the floor, the floor frame having spaced side portions and an end portion connected to an end region of each side portion, a swingable frame having spaced side portions and an end portion connected to an end region of each side portion, the opposite end regions of the side portions of the swingable frame being pivotally attached to the opposite end regions of the side portions of the floor frame, a stop means interconnecting adjacent side portions of the frames that limits the angular displacement of and normally retains the swingable frame in an extended, inclined position, a flexible material substantially bridging the frames and detachably secured to the respective end portions of each frame, the rack assembly being of inverted U-shape, the legs of the U-shaped rack comprising a pair of pivotally connected extension arms, and the connecting member comprising a bar, one of the arms of each leg being secured to the bar, the other arm of each leg being pivotally connected to the opposite end region of a side portion of the horizontally disposed frame and pivotally connected in overlapping relation to the first mentioned of said extension arms, stop means interconnecting adjacent overlapping portions of said arms to retain said arms in extended position, and a brace pivotally connected at one end to one of said extension arms and at the opposite end to the floor frame.

5. In a laundry protector and rack assembly adapted for use with an ironing board, the laundry protector comprising a laundry shielding floor frame normally disposed in a horizontal position on the floor underlying the ironing board, the floor frame being substantially of a U-shaped configuration having an end portion and spaced side portions, a swingable laundry protector frame of substantially rectangular configuration having an outermost end portion and spaced side portions, one end region of each side portion of the swingable frame being pivotally connected to the free end region of each side portion of the floor frame so as to adapt the swingable frame to lie in nested relation to the floor frame when in folded position, a stop means on a side portion of the floor frame which limits the angular displacement of the swingable frame, and serves to retain the swingable frame in an expanded inclined position, a flexible material substantially bridging the said frames, and detachably secured about the respective end portions of each frame, the rack assembly being of inverted U-shape, the legs of the U-shaped rack comprising a pair of pivotally connected extension arms, and the connecting member of said U-shaped rack comprising an elongated tubular bar, an auxiliary bar slidably received and contained in the tubular bar, and adapted to be extended to augment the effective length of the tubular bar, an extension arm of each leg secured to the tubular bar, the second co-acting extension arm of each leg having one end thereof pivotally connected to the opposite end region of a side portion of the floor frame, with the opposite arm end portion overlapping and pivotally connected to the first said extension arm, stop means interconnecting adjacent portions of said arms to retain said arms in extended position, and a brace having one end pivotally attached to an extension arm secured to the tubular bar and the opposite end pivotally attached to the floor frame, the extension arms and brace being adapted to retain the bars in extended position at substantially the same plane as the ironing board, and being adapted to collapse into a compact, folded arrangement.
